DESIGN FOR AN AMMUNITION ROUNDS INDICATOR

William H. Huenergardt, Chicago, Ill.

Application March 10, 1943, Serial No. 109,710

Term of patent 14 years

To all whom it may concern:

Be it known that I, William H. Huenergardt, a citizen of the United States, residing at Chicago, in the county of Cook and State of Illinois, have invented a new, original and ornamental Design for an Ammunition Rounds Indicator, of which the following is a specification, reference being made to the accompanying drawing, forming part thereof.

Figure 1 is a front view of an ammunition rounds indicator, showing my new design.

Figure 2 is a side elevation of the same.

Figure 3 is a rear elevation of the same.

I claim:

The ornamental design for an ammunition rounds indicator, substantially as shown.

WILLIAM H. HUENERGARDT.
